60,048.

Patented Dec. 20, 1921.

Inventor

Samuel Messina.

By

Lucy Lacy, Attorney.

UNITED STATES PATENT OFFICE.

SAMUEL MESSINA, OF JAMESTOWN, NEW YORK.

DESIGN FOR A RUBBER HEEL.

60,048.

Specification for Design.

Patented Dec. 20, 1921.

Application filed March 31, 1921. Serial No. 457,532. Term of patent 7 years.

To all whom it may concern:

Be it known that I, SAMUEL MESSINA, a citizen of the United States of America, residing at Jamestown, in the county of Chautauqua and State of New York, have invented a new, original, and ornamental Design for a Rubber Heel, of which the following is a specification, reference being had

to the accompanying drawing, forming part thereof.

The drawing is a plan view of a rubber heel showing my new design.

I claim:

The ornamental design for a rubber heel, as shown.

SAMUEL MESSINA. [L. S.]
